UNITED STATES PATENT OFFICE.

BERNICE DELEMAR WEST, OF NEW YORK, N. Y.

DESIGN FOR AN ASH TRAY OR SIMILAR ARTICLE.

Application filed January 2, 1929. Serial No. 29,477. Term of patent 3½ years.

To all whom it may concern:

Be it known that I, BERNICE DELEMAR WEST, a citizen of the United States of America, residing at No. 140 East 63d Street, in the borough of Manhattan, city, county and State of New York, have invented a new, original and ornamental Design for an Ash Tray or Similar Article, of which the following is a specification, reference being had to the accompanying drawing, forming a part thereof, and showing, in—

Fig. 1 a front view in isometric perspective, and in Fig. 2 a side view in isometric perspective of an ash tray embodying my design.

I claim:

The ornamental design for an ash tray or similar article substantially as shown and described.

BERNICE DELEMAR WEST.
